UNITED STATES PATENT OFFICE.

ROBERT C. CHOPE, OF SYRACUSE, NEW YORK.

RAILROAD-GATE.

SPECIFICATION forming part of Letters Patent No. 333,829, dated January 5, 1886.

Application filed August 7, 1885. Serial No. 173,810. (No model.)

To all whom it may concern:

Be it known that I, ROBERT C. CHOPE, of Syracuse, in the county of Onondaga, in the State of New York, have invented new and useful Improvements in Railroad-Gates, of which the following, taken in connection with the accompanying drawings, is a full, clear, and exact description.

This invention relates to the class of gates in which a cable or chain is extended horizontally across the road, and supported by another cable or chain connected with the central portion of said horizontal cable or chain, and extended over a pulley on the upper end of a post, and having connected to its pendent free end a counter-weight, which produces the requisite tension on the said supporting cable or chain.

The object of my invention is to dispense with the aforesaid counter-weight and facilitate the operation of the gate; and to that end my invention consists in the novel construction and combination of parts, hereinafter fully described, and specifically set forth in the claim.

In the annexed drawings, Figure I is a front elevation of my improved gate, with some portions broken away to better illustrate some of the details; and Fig. II is a vertical section on line $\alpha\alpha$, Fig. I, with portions broken away for the purpose before stated.

Similar letters of reference indicate corresponding parts.

E and E' represent two standards erected at opposite sides of the highway or street to be guarded.

D D are the bars pivoted on said standards to swing in a vertical plane. Said bars are overbalanced by a weighted extension, D', back of the fulcrum, so as to carry them automatically to an erect position, as represented in the drawings. They are thrown into a horizontal position by means of a cable or chain, B, attached at one end to the foot of one of the standards E, and extending thence over a pulley, a, on the free end of the bar D, which is pivoted on said standard, thence across the road to a pulley, a, on the free end of the other bar D, thence to a pulley, b, on the foot of the standard E', to which the latter bar

is pivoted, and thence to a drum or winch, C, pivoted on said standard, upon which drum the said cable or chain is wound. In many cases the bars D D reach only part way across the road, and the cable or chain B completes the barrier between the ends of the bars when drawn down into a horizontal position, the bars being, however, of sufficient length to carry the cable or chain B a proper elevation above the road for the passage of vehicles carrying high loads, when the bars are raised into their vertical position, as represented in the drawings. The central portion of this barrier cable or chain B is supported by posts P P, erected at opposite sides of the highway, and reaching above the bars D D when in a vertical position. A stiff rod, r, is extended from the top of one to the top of the other of said posts, and from the central portion of this rod are suspended the pulleys c c, over which run the two branches of the chain or cable A, the extremities of said branches being connected with the horizontal portion of the cable or chain B, and the cable or chain A being extended over a pulley, d, pivoted on the upper end of the post P, adjacent to the standard E', as shown in Fig. I of the drawings. From the pulley d the cable or chain A is extended to a pulley, b', pivoted to the lower portion of the standard E', and thence to the drum or winch C, on which it is wound in opposite direction from the cable or chain B. In turning the drum or winch C in one direction the cable or chain B is wound up, and thereby caused to draw down the bars D D to close the gate, as represented by dotted lines in Fig. I of the drawings. Simultaneously with this action the cable or chain A is unwound from the drum with the requisite velocity, and thus the pendent portions of the branches thereof are lowered to conform to the descending barrier cable or chain B.

The described cables or chains B and A, when properly adjusted to the requisite tension, will operate perfectly in unison with each other, and, if desired, said cables or chains may consist of one continuous piece.

It will be observed that by my improvements the weight heretofore employed for drawing up the supporting cable or chain A is dis-

pensed with, and therefore the operation of the gate is facilitated.

Having described my invention, what I claim as new, and desire to secure by Letters Patent, 5 is—

The combination, with the vertically-swinging gate-bars D D, drum C, bar-operating cable or chain B, wound on said drum, posts P P, rod r, and pulleys c c and d, of the supporting cable or chain A, wound on the drum in opposite direction from the cable or chain B, substantially as described and shown.

In testimony whereof I have hereunto signed my name and affixed my seal, in the presence of two attesting witnesses, at Syracuse, in the 15 county of Onondaga, in the State of New York, this 3d day of August, 1885.

ROBERT C. CHOPE. [L. S.]
